UNITED STATES PATENT OFFICE.

GEORGE TATLOCK, OF SALEM, INDIANA.

IMPROVEMENT IN RAKING ATTACHMENTS FOR HARVESTING-MACHINES.

Specification forming part of Letters Patent No. 23,959, dated May 10, 1859.

To all whom it may concern:

Be it known that I, GEORGE TATLOCK, of Salem, in the county of Washington and State of Indiana, have invented a new and Improved Raking Attachment for Harvesters; and I do hereby declare that the following is a full, clear, and exact description of the same, reference being had to the annexed drawings, making a part of this specification, in which—

Figure 1 is a front view of my invention applied to the platform of a harvester; Fig. 2, a side view of the same; Fig. 3, a plan or top view of the same.

Similar letters of reference indicate corresponding parts in the several figures.

This invention relates to an improvement in that class of raking devices in which a rake-head is made to traverse over the platform in a direction parallel with the sickle, or at right angles, with the line of draft. The object of the invention is to give the above-described movement to the rake-head, and also the necessary rising-and-falling movement of the same at the termination of its strokes by a very simple means. They may be readily applied to harvesters, and admit of being very directly connected to the driving-wheel.

To enable those skilled in the art to fully understand and construct my invention, I will proceed to describe it.

A represents the platform of a harvester, on the upper surface of which a series of parallel strips or bars, a, are secured at equal distances apart, the spaces between the bars being sufficiently wide to receive the lower ends of the rake-teeth.

To the back part of the platform A two parallel bars, B B are placed, one being over the other in the same vertical plane, as shown in Fig. 1, and having a sliding bar, C, fitted thereon. In the upper end of this bar C a rake-head, D, is fitted and secured by a pivot, b, the rake-head being allowed to work freely on the pivot.

To the rake-head D, at a point quite near to the bar C, an arm, E, is attached by a pivot, c. This arm E is fitted in a loop or guide, d, attached to the bar C, said loop being sufficiently large to admit of a certain degree of play of the arm, which has a spring, e, attached to its back side, said spring having a tendency to keep the lower part of the arm thrown outward from the bar C. In the outer surface of

the arm E a notch is made to form a step-like projection, f, which, when the rake-head is elevated, as shown in black in Fig. 2, rests on the loop or guide d, said projection f serving as a support for the rake-head when the latter is elevated. This will be clearly understood by referring to Fig. 2.

At the outer side of the platform A there is a horizontal curved or slightly-oblique bar or arm, g, which is attached to an upright, h, to which one end of the bars B B are also attached, and to the inner or opposite side of the platform a bar or arm, i, is attached, said bar or arm being slightly inclined, as shown in Fig. 1. In the back side of the bar C a vertical slot is made to receive the pin j at the end of an arm, k, which is attached to one end of a shaft, l, having its bearing m on the upper part of a frame, n, which is attached to the platform A.

To the opposite end of this shaft l an arm, o, is attached, the lower end of which is attached to a connecting-rod, p, which is driven by a crank, q, from a shaft, r. The connecting-rod p is attached to the lower part of the arm o by a bolt, o', that passes through an oblong slot in said arm. By attaching the rod p higher or lower to the arm o the length of movement or stroke of the rake-head may be regulated as desired.

To the bar C a horizontal rod, s, is attached, said rod passing through the curve or bend t, that connects the two bars B B. The rod s serves as a guide, and insures an easy movement of the bar C.

The operation is as follows: The shaft r is connected with the driving-wheel of the harvester by a simple bevel-gearing, and as the harvester is drawn along a rotary motion is given the shaft r, and an oscillating movement is communicated from shaft r to shaft l by the connecting-rod p and arm o. The arm k of shaft l gives a reciprocating movement to the bar C, and consequently to the rake-head D, the pin j of arm k working up and down in the slot in the back of the bar C. Each time the rake-head D reaches the inner side of the platform A the rake-head is raised, in consequence of the lower end of the arm E passing up the inclined bar or arm i, and when said arm is at a certain height its spring e will thrust the projection f over the loop or guide d, and the rake-head will be supported in an elevated position,

as shown in black, Fig. 2, while moving to the outer side of the platform, and when it reaches the outer side the bar or arm *g* throws inward the arm *E*, and thereby frees the projection *f* from the loop or guide *d*, and the rake-head descends by its own gravity, its teeth *a* resting on the platform between the bars *a*, and as the rake is moved toward the inner side of the platform it rakes the cut grain therefrom and discharges it on the ground between the platform and the main frame of the machine. When the rake-head reaches the inner side of the platform it, as before stated, is raised, in consequence of the bar *D* passing up the inclined bar or arm *i*, and as the rake-head moves to the outer side of the platform in an elevated state the platform receives the cut grain, that is raked off from it, as before, during the succeeding movement of the rake-head to the inner side of the platform.

This invention, it will be seen, is extremely simple. The rake-head has a positive reciprocating motion given it by the employment of a very few parts, and the rising-and-falling movement is effected by an extremely simple

arrangement. There are no parts liable to become deranged by use, and none that cannot be readily repaired when necessary.

I do not claim broadly, irrespective of construction and arrangement, as herein shown and described, the employment or use of a reciprocating rake-head, for they have been used and operated in various ways; but

I do claim as new and desire to secure by Letters Patent—

Operating the rake-head *D*, which is pivoted to the sliding bar *C*, through the medium of the rotating shaft *r*, connecting-rod *p*, and rock-shaft *l*, connected respectively with the rod *p* and sliding bar *C* by the arms *k o*, in connection with the arm, *E* attached to the rake-head, the loop or guide *d*, attached to the arm *E*, and the bars or arms *g i*, attached to the platform, the whole being arranged substantially as and for the purpose set forth.

GEORGE TATLOCK.
